ATTORNEY

UNITED STATES PATENT OFFICE.

WILLIAM D. KYLE, OF MILWAUKEE, WISCONSIN, ASSIGNOR TO LINE MATERIAL COMPANY, OF SOUTH MILWAUKEE, WISCONSIN, A CORPORATION OF WISCONSIN.

PIN FOR INSULATORS.

Application filed November 15, 1922. Serial No. 601,070.

To all whom it may concern:

Be it known that I, WILLIAM D. KYLE, a citizen of the United States, and resident of Milwaukee, in the county of Milwaukee, 5 and State of Wisconsin, have invented new and useful Improvements in Pins for Insulators, of which the following is a description, reference being had to the accompanying drawings, which are a part of this specification.

The invention relates to insulator pins.

The object of the invention is to provide an insulator pin in which the metal pin is provided with soft metal portions threaded 15 to receive the insulator, the soft metal forming a cushion to prevent cracking of the insulator when screwing it onto the pin and prevent its cracking due to possible contraction and expansion of the metal pin when in 20 use.

The invention further consists in the several features hereinafter set forth and more particularly defined by claims at the conclusion hereof.

In the drawing: Fig. 1 is a view of an insulator pin embodying the invention, parts being broken away and parts being shown in section; Fig. 2 is a top view of the pin shown in Fig. 1; Fig. 3 is a section taken 25 on the line 3—3 of Fig. 1; Fig. 4 is a detail view of a modified form of insulator pin, parts being broken away and parts being shown in section; Fig. 5 is a top view of the insulator pin shown in Fig. 4; Fig. 6 is a detail view of a modified form of insulator pin, parts being broken away and parts being 30 shown in section, and Fig. 7 is a top view of the insulator pin shown in Fig. 6.

In each instance the insulator pin includes 40 a metal pin member 8, having a shank portion 9 threaded at its outer end 10, and a conical or tapered head portion 11. The shank portion 9 is provided with a boss or flange portion 12 so that the pin may be secured to a cross-arm 13, or other suitable support, by a clamping engagement of said arm between the portion 12 and a clamping nut 14.

Referring to Figs. 1 to 3, inclusive, the 45 head portion 11 is provided with a plurality of longitudinally extending grooves 15 and a square shoulder portion 16. A soft metal member 17 has strip portions 18 preferably joined together at their top 19 and to a ring portion 20 at the bottom. These strip

portions 18 fit within the grooves 15 and project from the head with their outer edges 21 indented to form a thread to receive the insulator 22. The ring portion 20 engages over shouldered portion 16 so that the strips 60 are held between the top 19 and the ring against longitudinal movement with respect to the head while their key connection with the head prevents their lateral movement with respect thereto. The member 17 may 65 be cast separately and slipped over the head and the ring portion 20 peened down against the base of the head, or said member may be die cast onto the head.

In Figs. 4 and 5 I show the head provided with longitudinally extending dovetail grooves 22 for separate strips 23 which have a fit in said grooves and have their outer edges 24 threaded to receive the insulator. The upper ends 25 of these strips may be 70 upset into recesses 25' and the lower ends 26 upset into recesses 27 to prevent longitudinal movement of said strips with respect to the pin member.

In Figs. 6 and 7 I show the head provided with longitudinally extending grooves 28 or receiving wires 29, preferably oval in cross-section, and provided with indentations 30 to form a thread for the insulator. One of these wires 29 is bent upon itself 80 over the head of the insulator and into a transverse recess 31 formed in the head, and its ends are passed into a transverse opening 32 at the base of the head and the other wire 85 is similarly bent upon itself over the head of the insulator and into a transverse groove 33 formed in the head and its ends are passed into a transverse opening 34 at the base of the head, thus holding the wires 90 against longitudinal movement with respect to the head.

From the foregoing description it will be noted that in each instance the soft metal cushion upon which the insulator is fitted is formed by a plurality of soft metal strips 100 keyed to the head of the pin member and having their outer edges threaded to take the insulator, and that provision is made for preventing longitudinal movement of said strips relative to said pin member. It 105 will also be noted that the slots in the head are formed parallel to the inclined surface of the head and the strips are thus inclined to provide a tapered thread for the insulator.

The soft metal member 17 forms, in effect,

a sleeve member surrounding the head of the pin with the top 19 abutting against the outer end of the head and the ring 20 abutting against the shouldered portions of the 5 inner end of the head, thus retaining the soft metal member against longitudinal movement.

What I claim as my invention is:

1. In an insulator pin, the combination of 10 a metal pin having a head, and longitudinally extending soft metal strips having a key connection with said head and having inwardly projecting parts at their ends to hold them against longitudinal movement relative 15 to said head, the outer edges of said strips being indented to form threads for receiving an insulator.
2. In an insulator pin, the combination of 20 a metal pin having a head, longitudinally extending soft metal strips having a key connection with said head and having outer indented edges forming threads for the insulator, and means for holding said strips against longitudinal movement relative to 25 said head.
3. In an insulator pin, the combination of a metal pin member having a head, longitudinally extending soft metal strips joined together at their upper and lower ends over

the top and beneath the base of said head 30 and having a key connection with said head and indented outer edges forming threads for the insulator.

4. In an insulator pin, the combination of a metal pin having a head, longitudinally 35 extending soft metal strips having a key connection with said head and having outer indented edges forming threads to receive an insulator, and means for holding said strips against longitudinal and outward radial movement relative to said head.

5. In an insulator pin, the combination of a metal pin member having a head, longitudinally extending soft metal wire strips having a key connection with said head and 45 indented outer edges forming threads for the insulator, and means securing said strips against longitudinal movement.

6. In an insulator pin, the combination of a metal pin member having a conical head, 50 a soft metal sleeve member disposed on said head and having peripherally-spaced longitudinally-extending threaded portions with which the insulator engages, and means for retaining said member in place.

In testimony whereof, I affix my signature.

WILLIAM D. KYLE.
